UNITED STATES PATENT OFFICE

2,448,990

MATCH PACKAGE

Arthur O. Levine, Brooklyn, N. Y.

Application May 22, 1946, Serial No. 671,510

2 Claims. (Cl. 46—11)

1

This invention relates to match packages, and the like, and has for one of its objects the production of a novel type of package or match book which will stimulate the curiosity of an observer and provide an efficient advertising means.

A further object of this invention is the production of a simple and efficient match package, which will constitute an efficient advertising medium in restaurants, and the like, and which will be so novel and attractive as to cause a patron to pick up the match package and take it home as a souvenir.

Other objects and advantages of this invention will appear throughout the following specification and claims.

In the drawing:

Figure 1 is a front view of the match package;

Figure 2 is a side elevational view, certain parts being shown in section;

Figure 3 is a top plan view;

Figure 4 is a front elevational view of the front flap or cover section of the package illustrating the positions of the various match-receiving apertures.

By referring to the drawing it will be seen that 10 designates the front flap or cover section of the match package which is adapted to be folded over in front of the back wall or section 11 of the package in the conventional manner, as shown in Figure 2. A comb-like strip of matches 13 of the conventional type is carried between the upturned flap or lip 14 of the back wall 11 in the conventional manner, and the lower edge 15 of the front flap 10 is adapted to be fitted behind this lip 14 when the package is closed, or as shown in dotted lines in Figure 2 when desired.

The front flap or cover section 10 is preferably provided with a pictorial illustration of a figure 16 having apertures 17 and 17^a located at the junction of the arms and legs, or the legs alone, with the body of the figure as shown in Figure 1. It is not desired, however, to limit the invention to the type of figure shown, for any type of figure may be substituted for the one illustrated without departing from the spirit of the invention. It is necessary that the apertures 17 and 17^a be located at a point adjoining the body 16 of the figure to give the desired pictorial effect illustrated in the drawing.

Certain match stems 18 of the match strip 13 are preferably bent substantially at right-angles to the strip 13. The outer heads 19 thereof are inserted through the apertures 17 of the front flap 10 in diverging relation with respect to one

another in the manner shown, to protrude beyond the front flap 10 and to simulate arms and hands of the figure 16. The arms 18 by extending through the apertures 17 in diverging relation will tend to limit the outward swing of the cover section 10 relative to the back wall or section 11 even though the lower edge 15 of the cover section 10 should become disengaged from the lip 14. This function is obvious when considering Figures 1 and 2.

Certain other match stems 20 and 21 are preferably bent substantially at right-angles to the strip 13 and are selectively extended through the apertures 17^a. The outer extremity 20^a of the match stem 20 is preferably bent downwardly to simulate a leg bent at the knee joint. The outer extremity 21^a of the match stem 21 is also preferably bent downwardly and is extended across the extremity 20^a of the stem 20 in cross-leg fashion to simulate crossing of legs. The outer heads 22 of the stems 20 and 21 simulate feet. The position of the stems 20 and 21, and the extremities 20^a and 21^a will also assist in preventing the cover section 10 from swinging to a wide open position and will therefore assist in limiting the outward swing of the cover section 10 relative to the back wall section 11, thereby maintaining the pictorial display without distortion.

From the foregoing description it will be seen that a very attractive and entertaining novelty has been produced, and it should be understood that the match stems may be bent in any suitable manner, to simulate different portions of the limbs of the figure depicted upon the front flap 10, and that any suitable number of match stems may be used for a series of figures depicted upon the front flap 10, without departing from the spirit of the invention.

Having described the invention what is claimed is:

1. An article of manufacture of the class described comprising a match strip consisting of a plurality of match stems carried by a match book having a flap, said flap having a pictorial display of a figure upon one face thereof, said flap having apertures formed therein at selected locations relative to the pictorial illustration, and said match stems being extended through the apertures in diverging relation with their match heads protruding outwardly to complete the pictorial illustration on the flap to simulate limbs of said figure and to limit the outward swing of the flap relative to the book.
2. An article of manufacture of the class described comprising a match strip consisting of a

plurality of match stems carried by a match book having a flap, said flap having a pictorial display of a figure upon one face thereof, said flap having apertures formed therein at selected locations relative to the pictorial illustration, some of said match stems being extended through the apertures in diverging relation with their match heads protruding outwardly to complete the pictorial illustration on the flap to simulate arms of said figure, and others of said stems being bent downwardly and laterally to simulate legs of the figure, the position of the match stems relative to the flap providing means to limit the

outward swing of the flap relative to the match book.
